SYSTEM OF COMPENSATING AUTOMATIC VOLUME CONTROL

R. Lee Hollingsworth, Riverhead, N. Y., assignor to Radio Corporation of America, a corporation of Delaware

Application June 27, 1934, Serial No. 732,565

9 Claims. (Cl. 250—8)

This invention relates to signalling devices of the type in which signal modulations on a carrier wave are converted into keying impulses and in which automatic volume control means is provided for maintaining the level of the signal comparatively constant irrespective of fluctuations in signal energy received and in which additional means is provided for controlling the automatic volume control means, so that a continuous marking impulse will not be produced by the system in the absence of signal carrying waves in the receiver.

When automatic volume control means is used with high gain receivers the full gain or amplification of the receiver may be applied suddenly upon the output circuit which may be a loud speaker, visual indicator, a line, or a telegraph keyer or any other apparatus, when the carrier energy is reduced to an extremely low value or when the carrier is completely removed.

This operation of the automatic volume control on receivers of radio telegraphy waves produces undesired results because if the automatic volume control is sufficiently fast, that is, of a small enough time constant to allow the receivers' gain to follow deep and fast fading properly, as the full gain of the receiver is attained due to a falling off of the energy in the received wave a large amount of energy is impressed upon the keyer. The same result occurs when the transmitting station ceases to send out signals for a short period of time. When the full gain, including the existing noise amplified to a very high level, is impressed or applied to the keyer, it causes a steady direct current impulse or tone, or in other words a continuous marking impulse, to flow through the line to the recording apparatus. This is a very undesirable condition and among other things leads the operators to believe that insofar as they can judge the transmitting station is sending out a continuous dash, indicating a possible source of trouble within the transmitting circuit.

An object of the present invention is to provide a practical method of and means for overcoming the production of this continuous marking impulse when the received signal strength falls below a useable value or the transmitter ceases sending. Briefly, this object of the present invention is accomplished by the use of a biasing potential supply in addition to the potential supply provided for automatic volume control purposes. This additional supply increases and decreases in amplitude as the supply of potential heretofore utilized for automatic

volume control purposes decreases and increases. Each of the biasing potential sources acts to supplement the action of the other source and consequently the amount and sensitivity of the automatic volume control.

A feature of the present invention is that in addition to controlling the receiver so that the absence of signals or the falling off of the amplitude of the signals does not produce what appears to be a continuous dash in the output of the converter but does increase the sensitivity of the keying device and insures a more complete signal to be obtained from a varying wave. Moreover, the present method and means permits the sensitivity and the gain of the converting device to be regulated over a range sufficient to operate successively on signals of varying strength and character. The novel features of my invention have been pointed out with particularity in the claims appended to the specification.

The nature of my invention and the manner in which the same may be utilized will be better understood from the following detailed description thereof and therefrom when read in connection with the attached drawings throughout which insofar as possible like characters indicate like parts and in which;

Figure 1 illustrates a preferred embodiment of a circuit arrangement including the essential elements of a receiver including my automatic volume control and compensating means;

Figures 2 and 3 illustrate modifications of the arrangement of Figure 1, while;

Figure 4 is a graph illustrating the operation of the devices illustrated in Figures 1 to 3 inclusive.

Referring to the drawings, and in particular to Figure 1, A, is an aerial system connected with a radio frequency amplifier, demodulator and audio frequency amplifier B. In practice the aerial system A may be replaced by a transmission line of the desired character. The radio frequency amplifier in the receiver B may be of the tuned radio frequency type or of the heterodyne type or any other known type. Energy from the output of the demodulator in B is applied directly or by way of audio frequency amplifiers in B to the input of a rectifier C. The rectifier C may be of any type known. Rectified current from the output of the rectifier C is passed through a low pass filter LP comprising series inductances and parallel capacities connected as shown. The filtered energy from the output of the filter LP is passed through a resist-

ance R_1 . A keying tube T_2 has its control grid connected as shown to a point on the resistance R_1 . The anode of T_2 is connected as shown by way of a source of potential and a resistance 5 R_5 to ground and from ground to the cathode of T_2 . A point on the anode circuit of T_2 is connected to the electrical center of the secondary winding of a transformer T_4 , the primary windings of which are connected as shown to a 10 source of tone frequencies TG . The terminals of the secondary winding of T_4 is connected to the control grids of a pair of thermionic tubes 10 and 12. The output electrodes of these tubes are coupled by a transformer T_5 to any utilization 15 circuit such as a long line or a recording device. Received signals are rectified in C . The rectified signal impulse components are smoothed in LP and appear across R_1 . The control grid of T_2 is biased to a point at which the tube is 20 normally conductive so that current flows in the anode circuit and consequently in the resistance R_5 . The flow of signal impulses through R_1 produce a potential drop so that the control grid of T_2 becomes less positive thereby cutting the flow 25 of current in the anode circuit and consequently in the resistance R_5 . This causes a rise of positive potential on the control grids of tubes 10 and 12 with respect to their cathode potential, which are connected to a point on the anode circuit of tube T_2 . This rise of potential causes the tubes 10 and 12, which are normally biased, to cut 30 off to become conductive and permit oscillations at tone frequency to be transferred from the source TG to the outgoing line for keying or recording purposes.

The output of the low-pass filter LP is also connected by way of a resistance R_2 and a line AVC to the unit B , and/or to the unit C , to supply thereto a direct current potential determined by 40 the intensity of the received wave for control purposes. This direct current potential may be applied to the control grid of one of the radio frequency amplifiers or any other tube in the unit B , or to the grid of a rectifier in C , (grid controlled rectification) to render the same less negative 45 when the amplitude of the wave therein falls off and more negative should the amplitude of the wave therein exceed a predetermined value. A condenser TC which in part determines the time 50 constant of the circuit is connected as shown between a terminal of R_2 and ground.

In order to prevent the falling off of signal wave intensity or the stopping thereof, from producing the effect of a continuous marking impulse in the 55 receiver I provide a compensating circuit which will now be described. The compensating circuit comprises a control tube T_1 having its control grid connected as shown between the rectifier C and the low-pass filter LP . The anode of tube 60 T_1 is connected as shown by way of a source of potential and a choking inductance and a resistance R_4 to the cathode of T_1 . T_1 , like T_2 , is normally biased to a potential such that anode current flows through the anode circuit including 65 the resistance R_4 . When signals appear in C , however, current flows through the circuit to produce a potential drop therein which renders the grid of T_1 less positive, so that less or no current flows in the anode circuit of T_1 . The 70 potential drop across R_4 is supplied by way of a resistance R_3 to the condenser TC to determine in part the charge on said condenser. That portion of the resistance R_4 between the point on the potentiometer and ground is connected as shown in shunt with TC and is in effect in par-

allel with the circuits R_2 , R_1 which is also in parallel or in shunt with TC . When there is no signal voltage drop across R_1 , R_2 , the voltage drop across R_4 charges the condenser TC and produces a flow of current through R_2 , R_1 . T_1 and T_2 may draw some grid current which also flows through R_1 . This current produces a drop through R_1 which is added to the drop produced therein by the current flow, due to the potential in R_4 . Grid current in T_1 , T_2 is not necessary 10 for satisfactory operation. The drop of potential caused in R_1 by anode current from T_1 supplied from R_4 through R_3 and R_2 is small due to the proportionate values of these resistances.

As indicated above, when no signal is present, 15 the flow of current, and consequently the fall of potential through R_1 , is determined by the drop through R_4 alone or by the same supplemented by the potential produced in R_1 by grid current in T_1 , T_2 . The instant a signal is received current 20 flows through R_1 and the grid of T_1 becomes less positive so that grid current ceases to flow and the anode current is reduced to zero, or to a desired level. The potential drop through R_4 is 25 small so that no potential is applied to the condenser TC , for charging purposes. The condenser TC then discharges through R_3 and R_4 and to some extent through R_2 and R_1 the parallel path to ground until the flow of current in R_1 due to the incoming signal reaches a value 30 such as will reverse the current flow from R_1 through R_2 and start to recharge condenser TC with signal voltage. This circuit is completed from R_2 by way of R_3 and R_4 to ground. Thus when the signal voltage is low there is a parallel 35 discharge path from the condenser TC to effectively increase the rate of the receivers' gain when it is needed.

The main object of connecting the control grid of the control tube T_1 ahead of the filter LP 40 is to insure that T_1 is controlled; that is, biased or actuated sufficiently ahead of T_2 to allow the gain of the receiver as determined by the automatic volume control to start increasing by the time the current passes through the filter to operate the keying tube T_2 , in case the mean signal strength at this moment is very weak. This action can only be had when R_2 and R_3 are 45 comparatively small in value, causing the time lag circuits TC , R_1 , R_2 , R_3 , R_4 to be rather fast 50 so that the change in the gain of the receiver is almost instantaneous.

The operation of the receiver will now be explained. In explaining the operation three conditions of operation will be utilized.

First it will be assumed that no signal is being received. The movable point on R_1 is adjusted to a point somewhere near the above ground end of R_1 and the movable point on R_4 is adjusted to a point such as to cause the gain of the receiver 60 as determined by the automatic volume control circuits to be reduced to a point where noise peaks occasionally energize T_2 sufficiently to render the coupling tubes 10 and 12 conductive. Now if these points have been properly selected when 65 the current flows through R_1 it will produce across R_1 the exact amount of potential drop as is built up across R_1 and R_2 , due to the potential applied thereto from R_4 when there is incoming signal current. Under these circumstances the gain of 70 the receiver remains the same, except that the gain rises slightly at the start of all signal impulses, be they stronger or weaker than that required to produce through R_1 a voltage drop lesser than equal to, or greater than, that pro-

duced therein by the potential drop in R_4 . This particular action is shown graphically in Figure 4. When this condition exists, the automatic volume control supply simply changes from R_1 to R_4 without changing the gain of the receiver except as explained at the start of the change of the bias supply from R_4 to R_1 .

Under the second conditions of operation it will be assumed that I am using the same adjustments as used above. Now assume that the signal energy produces a drop through R_1 which is greater than the drop supplied by R_4 . The charge on the condenser TC is lessened at the start of the signal impulse, and the gain of the receiver increases for an instant as the signal voltage starts building up across R_1 . As the signal voltage increases the change of gain in the receiver is halted and finally reversed as the potential drop in R_1 begins to approach the drop supplied therein by R_4 and the gain is further reduced during this impulse in proportion to the strength of the signal. Between each signal impulse the gain rises, or starts to rise, to the value originally selected by adjustment of the movable point on R_4 . The speed of keying and the time constant of the automatic volume control circuits both govern the amount of gain that the receiver is allowed to increase between impulses.

Under the third condition of operation it will be assumed that the circuits have the same adjustments as before. However, it will be assumed that the potential drop across R_1 is somewhat less than the potential drop supplied thereto from R_4 . Under these circumstances one must keep in mind that the line keyer tube T_2 operates on a signal strength of one microvolt input to the receiver. The signal strength under such circumstances is almost always below the noise level. The automatic volume control tube T_1 is cut off first by the flow of potential in R_1 due to received signal and because of reduced plate voltage, and further because this tube is energized first. Therefore, when the signal voltage drop across R_1 is less than that supplied from R_4 the condenser TC discharges more rapidly through R_3 and R_4 and through R_2 and R_1 , the percentage of discharge through R_2 and R_1 depending upon the actual potential build up across R_1 by the received signal voltage. Here the gain of the receiver is increased during each signal impulse and decreased during the interval of time between impulses.

The overall receiver performance, as explained in connection with conditions 1, 2 and 3 are extremely desirable. The advantages obtained from this novel keying system are numerous. Under conditions 1 and 2, during initial adjustment the device is so set that the keyer operates as close to the noise level as practical. Due to the increased gain, as explained in condition 3, the signal even when fading below this value does not produce dropouts in the line signal because the gain of the receiver is increased with each impulse and consequently the signal can work into the noise level without the line signal actually stopping except under extreme conditions of fading. A large amount of the noise passed through the keyer on deep fades is filtered out in the line circuits following the coupling tubes 10 and 12 so that in practice a practically clean and complete signal is obtained even though the incoming signal strength falls below the noise level.

The arrangement shown in Figure 2 is in many respects similar to the arrangement shown in

Figure 1. However, in the arrangement of Figure 2 the control grid of T_1 is connected to the same point on the resistance R_1 that the control grid of T_2 is connected. The operation of T_1 ahead of T_2 is insured here due to the reduced voltage applied to the plate of T_2 . The tube T_2 draws its plate voltage from a voltage divider VD which is connected as shown across a common high potential source to supply the entire apparatus except for the cathode heating sources and the potential source PS connected with the anodes of the tube T_1 . The arrangement of Figure 2 is simplified in other respects as shown. The screen grids of tubes T_1 and T_2 may be connected as shown to a second voltage divider VD_2 .

In both circuits T_1 and T_2 draw grid current. In Figure 1 the grid current may be utilized as a fine adjustment of R_4 , because raising the arm of point on R_1 more above ground adds negative voltage to the charge applied to TC , thereby reducing the receiver's gain and decreasing the grid current of the tone keyer T_2 and likewise making it more sensitive simultaneously as the receiver gain is decreased. Where both grids are commonly connected to the arm of R_1 as in Figure 2 the amount of current drawn by the grid circuits of the tubes may be decreased as the point on R_1 is moved further above ground.

In this manner the plate current of T_1 and T_2 may be reduced to a point at which they are cut off readily. In this manner the sensitivity of the keying tube may be adjusted to as great a value as may be desired, but does not affect materially the gain of the receiver.

In many cases the necessity of using an additional tube T_2 for control purposes is not necessary. For example I may utilize an arrangement as shown in Figure 3. In the arrangement of Figure 3 the single tube T_2 serves as a keying tube to supply biasing potentials to the coupling tubes 10 and 12 to control the tone impulses sent out from the source TG over the line. The resistance R_4 in this circuit supplies the supplemental potentials for charging the condenser TC and for controlling the potential drop in R_2 , R_1 . The circuit otherwise is somewhat similar to the arrangement of Figure 1. This circuit, however, does not possess the feature of having the space bias operating in advance of the line keyer tube.

In operation when no signal is received the control grid of T_2 is sufficiently positive to permit a flow of current in the anode of T_2 and consequently in the resistance R_4 . The drop of potential through this resistance biases the tubes 10 and 12 to cut off so that no tone impulses can go out over the line. At the same time the potential drop through R_4 is applied through resistance R_3 to the automatic volume control circuit to supplement the action of T_1 as in Figure 1. The time constants of the automatic volume control circuit should be such as to permit the automatic volume control to act rapidly to increase the gain of the receiver as the keyer tube starts to cut off. On the reception of signals current flows in R_1 . The potential drop produced by said current in R_1 is applied to the control grid of T_2 and the flow of current in the anode circuit thereof decreases. The potential drop through R_4 decreases and the control grids of tubes 10 and 12 become more positive thereby permitting tone frequency impulses to be impressed on the line from the source TG . At the same time, there is less potential drop applied by way of resistance R_3 across TC and this condenser

is permitted to discharge through R_1 and R_2 depending upon the signal strength and the gain of the receiver varies inversely with the strength of the received signal.

5 The overall characteristics of my novel tone keyers of Figures 1 and 2 are shown in Figure 4 of the drawings. In this figure the current through R_1 (abscissas) is plotted against the plate current (ordinates) of the keyer tube T_2 10 and of the AVC tube T_1 and also against line volts at the output of the system.

Having thus described my invention and the operation thereof what I claim is:

15 1. The combination with a source of signal carrying waves, of means for converting said waves into direct current impulses characteristic of the signals comprising, a rectifier connected to said source, a low-pass filter connected to said rectifier, a discharge tube having its input electrodes connected to the output of said low-pass filter, a utilization circuit connected to the output of said tube, an automatic volume control circuit having two parallel branches, one of which includes said low-pass filter and a resistance, and 20 the other of which includes an additional tube and a resistance, and a connection between said automatic volume control circuit and said source of signal carrying waves.

25 2. The combination with signal carrying wave relaying means of the discharge tube type, a rectifier connected with said relaying means, an output circuit connected with said rectifier, a gain control device comprising a resistance and a condenser connected with the output of said rectifier and to a control electrode in a tube of said wave relaying means to control the relaying characteristic thereof in accordance with the amplitude of the wave, and a device for preventing said gain control from causing said relay to energize 30 said rectifier and said output circuit continuously in the absence of wave energy in said relaying means comprising a circuit including potential reversing means connecting in parallel with said resistance and condenser.

35 3. The combination with signal carrying wave amplifying means of a rectifier connected with said amplifying means, a filter circuit connected with said rectifier, an output tube, a control tube connecting said rectifier to a control electrode 40 of said output tube to determine the conductivity thereof, a gain control device comprising, a resistance and a condenser connected with the output of said filter and to control means in said wave amplifying means and a device for preventing said gain control from maintaining said output tube conductive continuously in the absence of wave energy in said amplifying means comprising a circuit including a potential reversing 45 means connected with the output of said rectifier and to said resistance and condenser.

50 4. The combination with signal carrying wave amplifying means of a rectifier connected with said amplifying means, an output tube, a control tube connecting said rectifier to a control electrode of said output tube to determine the conductivity thereof, a gain control device comprising, a resistance and a condenser connected with the output of said rectifier and to said wave amplifying means to increase the gain thereof when 55 the wave amplitude decreases and vice versa, and a device for preventing said gain control device from maintaining said output tube conductive continuously in the absence of wave energy in said amplifier means comprising a thermionic tube having its input electrodes connected to

said rectifier and its output electrodes connected by way of an impedance to said resistance and condenser.

5 5. In a signal keyed wave recording means, a wave amplifier, a rectifier coupled to the output of said amplifier, an impedance connected to the output of said rectifier, recording means controlled by the potential drop in said impedance, an automatic volume control circuit including an impedance and a condenser connected with the output of said rectifier and to said amplifier to control the gain thereof, and means for preventing said automatic volume control circuit from unduly increasing the gain of said amplifier in the absense of signal markings on said keyed wave 15 in said amplifier, comprising an additional impedance connected to the output of said rectifier, and means connecting said last named impedance in shunt to said condenser to control the charge of said condenser in a sense opposite that to which 20 the charge of said condenser is controlled by signal currents in the output of said rectifier.

6. A signal wave recording means as recited in claim 5 in which a filter circuit is connected between the output of said rectifier and said first 25 named impedance.

7. In a signal wave recording means, a wave amplifier of controllable gain, a rectifier connected with the output of said amplifier, a filter circuit connected to the output of said rectifier, an 30 impedance connected across the output of said filter circuit, a recording circuit connected to said impedance, an additional impedance connected to the output of said filter circuit, a condenser connected in shunt with said last named impedance, a circuit connecting said last named impedance to said amplifier to apply thereto a potential to control the gain thereof, a thermionic tube having its control grid connected to the output of said rectifier, an impedance connected 40 between the output electrodes of said thermionic tube, and a circuit connecting a point on said last named impedance to said second named impedance.

8. In signal wave recording means, wave amplifying means of controllable gain, a rectifier connected with the output thereof, a filter circuit connected to the output of said rectifier, a pair of impedances connected with the output of said filter circuit, a thermionic tube having its control grid connected to a point on one of said impedances, an additional impedance connected between the output electrodes of said thermionic tube, a recording circuit connected to a point on said additional impedance, a connection between 50 a point on said additional impedance and a point on the other of said first named impedances, and a connection between the other of said first named impedances and said amplifier for applying a potential thereto to control the gain thereof.

9. In combination, an antenna, a radio frequency amplifier coupled to said antenna, a detector for detecting the output of said amplifier, an automatic volume control circuit responsive to the output of said detector for controlling the 65 amplification of said radio frequency amplifier, a vacuum tube, means coupling input electrodes of said vacuum tube to said detector, a resistance connected between the output electrodes of said vacuum tube, and means variably connected to 70 said resistor for decreasing the amplification of said radio frequency amplifier in the absence of signal upon said antenna.
